UNITED STATES PATENT OFFICE.

EDMUND H. LUNKEN, OF CINCINNATI, OHIO, ASSIGNOR TO THE LUNKEN-HEIMER COMPANY, OF SAME PLACE.

DESIGN FOR A VALVE-CASING.

SPECIFICATION forming part of Design No. 25,720, dated June 30, 1896.

Application filed April 15, 1893. Serial No. 470,540. Term of patent 14 years.

To all whom it may concern:

Be it known that I, EDMUND H. LUNKEN, a citizen of the United States, residing at Cincinnati, in the county of Hamilton and State 5 of Ohio, have invented and produced a new and original Design for Valve-Casings, of which the following is a description, reference being had to the accompanying drawings, forming part of this specification.

10 My newly-designed valve shell or casing is intended for straightway or "gate" valves, and has for its object the production of a casing which shall be more compact, better proportioned, and more symmetrical in form, 15 and more pleasing and ornamental in appearance than those heretofore employed. Its novelty will be hereinafter set forth, and more particularly pointed out in the claims.

In the accompanying drawings, Figure 1 20 represents an end elevation of a valve embodying my newly-designed casing; Fig. 2, a perspective view of the same, the valve being turned on a vertical axis about forty-five degrees from the position of Fig. 1; and Fig. 25 3 a side elevation of the valve, the valve being turned ninety degrees from the position of Fig. 1.

The same letters of reference are used to indicate identical parts in all the figures.

30 The distinguishing feature of my design consists in the hood or bonnet portion of the casing, which is of novel shape and appearance and applied to the body portion of the valve in a novel manner, as will be hereinafter described more fully explained.

The shape and appearance of the body portion A of the valve, except as hereinafter pointed out, does not differ materially from valves heretofore in use. It is approximately circular in cross-section, contains the straight cylindrical passage B, which is adapted to be closed by a disk C, operated by the usual valve-stem D, having a handle or hand-wheel E at its upper end for turning it, 45 and has formed integral with its opposite ends the usual pipe connections F F. In the casing shown in the drawings the flanges of these pipe connections have polygonal peripheries, for the application of wrenches, and 50 the connections are interiorly threaded, but in valves of some sizes, and especially where

the bodies are made of iron, the flanges of the pipe connections have circular peripheries and the connections are not interiorly threaded, and as the novelty of my design does not 55 reside in this portion of the valve-casing I wish it understood that my invention contemplates both forms of flanges upon the pipe connections.

At the middle of its upper side the body 60 portion A of the valve is formed into a transverse rectangular extension G, extending substantially the full width of the valve. This rectangular extension G is quite narrow, 65 relatively to its length, its width in this instance being less than one-half of its length. It contains the narrow opening through which the valve-disk is lifted into the bonnet portion of the casing when the valve is opened. The extension is quite short, vertically, so 70 that its upper surface, upon which the bonnet portion of the casing rests, is only slightly removed from the cylindrical passage through the body, and in this respect it differs from the valves heretofore in use. This upper surface of the extension G is flat and adapted to 75 form a close joint with the flat under surface of the bonnet portion of the casing hereinafter described. Its upper end is shown as provided with a peripheral flange H, upon 80 which rests a corresponding flange I upon the lower edge of the bonnet portion, but these flanges may be omitted and are not essential parts of my design.

The bonnet or hood J of the valve consists 85 of a main portion or shell whose lower edge is approximately rectangular in shape and adapted to rest upon and fit the rectangular extension G of the body A.

The top of the bonnet J is formed into a 90 vertically-extending neck K, in this instance tubular in form and having screwed upon its upper end a polygonal nut L. At its opposite sides the bonnet J is provided with laterally-projecting ears M M, having flat upper surfaces and cut-away or curved under surfaces, 95 as at N. The vertical sides of the neck K and the horizontal upper surfaces of the ears M M are preferably connected by inclined surfaces O O, though the two surfaces may be connected by curved surfaces, or at right angles, 100 if desired. The opposite faces of the bonnet

are in this instance provided with shallow recesses P P. The connecting lower edge or wall of the two recesses upon each face of the bonnet forms a rib portion Q, extending nearly 5 the full width of the valve, and where the neck K is of tubular form, as in the present instance, the opposite faces of the bonnet are provided with convex swells or vertical extensions R of the opposite sides of the neck 10 K, the extensions R terminating at the upper edge of the rib Q and separating the two recesses P P.

Surrounding the middle of the body portion A of the easing, and in this instance fitting 15 in a shallow groove therein, is a U-shaped clip S, whose vertically-extending upper ends pass through holes in the ears M M of the bonnet and have screwed upon them nuts T T, which rest upon the flat upper surface of the 20 said ears. Where the upper surface of the extension G and the lower surface of the bonnet J are provided with the flanges H H, as in this instance, said flanges at the opposite ends 25 of these rectangular portions will be notched or rounded out to receive the ends of the clip S, as shown.

The essence of my new design consists in the bonnet J, whose novel distinguishing features are that it is quite thin relatively to its 30 width, has the vertically-extended neck portion K, and is provided with the laterally-projecting ears M M. Such being the case it is evident that the details of the design may be considerably varied without departing from 35 my invention. Thus the neck K need not be tubular in form. Its exterior may be polygonal or of other shapes than cylindrical, though it adds to the beauty of the design and the symmetry of the valve-easing to have it tubular in form, as shown. Even where tubular in form, however, the opposite faces of the 40 bonnet need not be provided with the vertical extensions R of the neck portion, and the re-

cesses P P and the rib Q, formed by them, may be omitted. Again, it is not essential that 45 the upper surface of the extension G of the valve-body and the lower surface of the bonnet should be exactly rectangular in shape, it being sufficient to come within my design if they are oblong in shape and quite narrow 50 relatively to their length transversely of the valve.

From the foregoing description it will be seen that my new design produces a valve-easing which is exceedingly compact, as compared with those heretofore in use, is symmetrical in form, and ornamental and pleasing to the eye, and that these results are chiefly accomplished by the novel shape of the bonnet or hood and its novel application to the 60 valve-body.

Having thus fully described my design, I claim—

1. The herein-described design for valve-easings, consisting of the body portion having 65 the opposite pipe connections, the wide and relatively-thin bonnet or hood portion fitted upon the body transversely to the latter and having the vertically-extending neck portion and laterally-projecting ears, the U-shaped 70 clip surrounding the body and passing at its upper ends through the opposite ears of the bonnet, and the nuts upon the ends of the clip above the ears of the bonnet, substantially as shown and described. 75

2. The herein-described design for the bonnet or hood of a valve-easing, said bonnet having the oblong main portion, the vertically-extending neck portion, and the laterally-projecting ears, substantially as shown and de- 80 scribed.

EDMUND H. LUNKEN.
